UNITED STATES PATENT OFFICE.

RUDOLPH J. LACKNER, OF NEW YORK, N. Y.

SCULLING-PROPELLER FOR VESSELS.

1,160,722.

Specification of Letters Patent. Patented Nov. 16, 1915.

Application filed October 20, 1913. Serial No. 796,289.

To all whom it may concern:

Be it known that I, RUDOLPH J. LACKNER, subject of the Emperor of Austria-Hungary, residing at New York, in the county of New 5 York and State of New York, have invented certain new and useful Improvements in Sculling-Propellers for Vessels, of which the following is a specification.

My invention relates to propelling mechanism and particularly to propelling mechanism for use on ships, boats, or as means 10 for propelling air craft.

The primary object of my invention is the provision of improved propelling mechanism for boats, etc., of a particularly simple 15 and efficient character.

A further object of my invention is to provide propelling mechanism so constructed as to secure a sculling action as distinguished from the action of the ordinary 20 screw propeller.

A further object is to provide a propeller for craft of all sorts constructed on the principle of the sculling blade and to provide 25 mechanism whereby the sculling blade may be operated.

A further object of the invention is to provide a plurality of sculling blades arranged to move across each other to thereby 30 secure a continuous propulsion of the vessel.

Still another object is to provide a propeller for vessels consisting of one or more sculling blades, each sculling blade being pivoted at one end and having its free end 35 swinging transversely and to provide means whereby these sculling blades may be operated.

Still another object is to provide in connection with a boat or other vessel one or 40 more sculling blades and to provide a casing within which said blades operate.

Still another object is to provide in connection with the sculling blades before mentioned, blade centralizing devices pivotally 45 connected to the sculling blades.

A further object is to provide in connection with sculling blades for propelling a vessel or like craft forward, means for reversing the movement of the vessel.

50 Still another object is the provision of sculling blades so constructed that they will

have not only a movement transverse to the longitudinal axis of the vessel but that they shall also have a rocking movement whereby to secure a more perfect sculling action. 55

Further objects will appear in the course of the following description.

My invention is illustrated in the accompanying drawings, in which:

Figure 1 is a side elevation of a motor 60 boat showing one form of my improved propeller applied thereto. Fig. 2 is a plan view of the construction shown in Fig. 1. Fig. 3 is a detail plan view of the rear end of a boat with my improved sculling propellers 65 in place thereon, the mechanism for operating the propellers being shown in dotted lines. Fig. 4 is a side elevation of the propellers shown in Fig. 3, the walls of the sculling case being partly in section. Fig. 70 5 is a perspective view of a modified form of sculling propeller. Fig. 6 is a diagrammatic plan view of the construction shown in Fig. 3 but showing by arrows the currents created by the movement of the propeller 75 blades. Fig. 7 is a like view to Fig. 6 but on a smaller scale and shows a modification of the construction shown in Figs. 3 and 6. Fig. 8 is a side elevation of one of the blades 80 and centralizers shown in Fig. 7. Fig. 9 is a series of sectional views taken across one 85 of the sculling blades to show the various sections which a sculling blade may have. Fig. 10 is a sectional plan view of the rear end of the motor boat showing the means for rotating the oscillating propeller blades around a central axis. Fig. 11 is a side elevation of the construction shown in Fig. 10. Fig. 12 is a diagrammatic rear end view 90 showing the action of spring blades when rotated. Fig. 13 is a fragmentary view showing the means for rotatably adjusting the blades shown in Figs. 10 and 11. Fig. 14 is a rear end elevation of the mechanism for continuously rotating the blades illustrated 95 in Figs. 10 and 11. Fig. 15 is a longitudinal sectional view of the rear end of a motor boat showing a different method of operating the blades. Fig. 16 is a transverse section of the arrangement shown in Fig. 15. 100 Fig. 17 is a detail view of a modified form of blade adapted to be used in the construc-

tion shown in Figs. 10 and 11. Fig. 18 is a diagrammatic view of a submarine boat provided with steering rudders adapted to be used in connection with my improved propeller.

Referring to the drawings A designates a motor boat or other vessel. While I have illustrated my improved sculling apparatus applied to a motor boat, it is to be understood that it may be applied to vessels of all types and that it may also be applied for the propulsion of air craft if desired.

The vessel A may be of any suitable form and is provided with engines B shown in dotted lines in Fig. 2, which may be of any suitable type. At the stern of the vessel is the scull compartment or case designated 2. The rear end of this compartment is open and in plan view the compartment is approximately diamond-shaped, the rear end of the diamond being truncated. As illustrated in Figs. 3 and 4 there is disposed in this compartment one pair or a plurality of pairs of sculling blades. As illustrated in Figs. 3 and 4 and in Fig. 2, there is one pair of blades 3, one of these blades being designated 3^a to distinguish it from the opposite blade 3. The blade 3^a is disposed on a higher level than the blade 3 so that the blades may move past each other transversely of the longitudinal axis of the boat. The forward ends of the blades are pivoted upon a common pivot, as for instance, upon the bolt 4, the forward ends of the blades being formed with knuckles 5 for this purpose. The blades are designed to shift entirely across the width of the scull case 2 so that when so reciprocated the blade 3^a, for instance, will take the position of the blade 3 in Fig. 2, while the blade 3 will take the position of the blade 3^a.

Preferrably each blade is pivotally attached at its rear end to a blade centralizer 6. There are two of these blade centralizers, one for each blade, and the rear ends of these centralizers are pivoted to a common pivot pin, as for instance, the bolt 7. As illustrated, this bolt 7 passes down through a guide yoke 8 and at its lower end passes through a like guide yoke 9. These guide yokes are longitudinally slotted as at 10 and are supported at top and bottom of the rear opening of the scull case 2. The longitudinal slot 10 permits the pintle bolt 7 to reciprocate but holds this pintle bolt in a vertical plane coincident with the vertical axis of the vessel. As illustrated, a rudder 11 is also hingedly supported in any suitable manner upon the guide yokes 8 and 9, this rudder being shown as provided with the outwardly projecting rudder arms 12 whereby it may be operated. It is to be understood, however, that the particular form of rudder or the particular mechanism for

operating it forms no part of my present invention. The blades 3 and 3^a are adapted to be shifted transversely across the scull chamber or case 2 by any suitable means and I have shown for this purpose the eccentrics or crank disks 13, each mounted upon a shaft 14 which shaft carries the beveled gear 15 driven by means of a beveled gear 16 mounted upon a longitudinal shaft 17. There is a drive mechanism for each blade. As illustrated, these shafts extend forward and are operatively connected to the engine B. Each propeller blade 3 or 3^a is operatively connected to its corresponding eccentric 13 by means of a connecting rod 18. It will be obvious, therefore, that the rotation of the shafts 17 will cause a transverse oscillation of the blades 3 and 3^a and a transverse oscillation of the centralizers 6. As illustrated, each of the sculling blades is connected to its corresponding centralizer 6 by means of a hinged joint and a pintle 19 but the particular form of this joint may be modified without departing from the spirit of the invention.

The blades 3 and 3^a may have any desired cross sectional form and a number of such forms are illustrated in Fig. 9. These forms are fully disclosed and, therefore, require no special description and it will be understood that the cross sectional form of the blade will depend upon the work to be done or the circumstances of use. In all the other figures of the drawings the I-beam type of blade has been illustrated for the sake of simplicity.

In Fig. 5 I have illustrated a form of my invention which is practically the same as that shown in Figs. 3 and 4 but in which there are a pair of blades on each side. In this figure, 20 and 20^a designate the upper and lower blades respectively of one pair and 20^b and 20^c designate the corresponding blades of the opposite pair. It will be seen that the blades of one pair are vertically spaced from each other and the blades of the other pair are also spaced from each other and interposed between the blades of the first pair. All of the blades are formed at their forward ends with the knuckles 5 through which passes the pintle pin 4^a. To the rear end of each blade is hingedly connected a centralizer 6^a, these centralizers being pivotally or hingedly connected to each other by means of the pintle or pivot pin 7^a. While the yokes 8 and 9 are not shown in Fig. 5, it is to be understood, of course, that the pintle 7^a extends through the yokes in exactly the same manner as is illustrated in Fig. 4 so as to permit a longitudinal reciprocation of the pintle 7^a to permit the oscillation of the blades.

In Fig. 1 I show a construction very similar to that illustrated in Fig. 4 but in which

the blades 21 are vertically spaced from each other a distance sufficient to accommodate the longitudinally extending propeller shaft 22. This propeller shaft is driven 5 from the engine B in any suitable or usual manner. It is, however, not used for propelling the vessel forward but for the purpose of reversing the movement of the vessel, it being plain that with only one set of 10 sculling blades disposed in the stern of the boat it will be impossible to move the vessel rearward.

In Fig. 6 is illustrated diagrammatically the action of the sculling blades illustrated 15 in Fig. 3, it being understood, however, that the action is precisely the same for the construction shown in Fig. 5. In Fig. 6 it is assumed that the blades are moving laterally outward in the direction of the arrows and that to take the position shown in 20 Fig. 6 the blades 3 and 3^a have shifted toward each other to a median position and then shifted outward in the same direction until the blade 3^a is on the port side of the 25 boat and the blade 3 on the starboard side of the boat. As the blades move toward each other, that is; move from the position shown in Fig. 3 to a median position shown in dotted lines in Fig. 6, the water will be 30 compressed in the space between the blades and will be forced rearward as shown by the arrows in Fig. 7, while water will be drawn inward between each blade and the corresponding side of the scull case or chamber. After the blades have passed each 35 other and such median position and commence to move away from each other, water will be drawn into the space between the blades 40 and the sides of the scull case or chamber will be forced outward as illustrated by the arrows in Fig. 6.

It is thus to be seen that power is secured 45 by the sculling blades being forced across each other and pulled back again, each blade operating in the manner of a fish's tail or the tail of an eel and two or more blades operating analogously to the tails of a plurality of fish or eels moving, however, 50 in opposite directions.

By disposing of the sculling blades within an inclosed scull case or chamber I prevent dragging and produce a steady and continuous straight-ahead drive. Furthermore, by 55 inclosing the sculls within the case or chamber 2 I obtain not only the compression of the water on the side toward which the blade is moving but the suction on the opposite side of the blade assists almost as much 60 as the compression of the water to propel the boat or ship forward. This is caused by the suction of the moving blade compelling water to flow into the scull case or chamber 2 and the inflowing water contacts with the

wall of the scull case, forcing the boat forward. This action is particularly effective and not only is a great increase in speed secured but this increase is secured at a saving in fuel and power over present devices. Furthermore, it will be seen that the blade 70 centralizers act to cause a compression of the water and force the water rearward. While I do not wish to limit myself to the use of these blade centralizers I prefer to use them 75 for the purpose of steadyng the blades, equalizing their movement, and for the additional effect secured by the action of the centralizers upon the blades. It will be noted that the shape of the chamber or case 2 conforms to the shape taken by the blades 80 when they are opened out and that when these blades are opened out, that is; in the position shown in Fig. 6 or Fig. 2, a wide outlet is provided for the water so that there 85 is no choking action and that the same outlet is practically secured when the blades move into alinement with each other at their median position.

In Fig. 7 I have illustrated diagrammatically another form of my invention which 90 operates, however, on exactly the same principle as the one heretofore described. In this form, however, the blades 20^a are not pivotally or hingedly mounted at their forward ends upon a common hinge pintle but each 95 is mounted on a separate pintle designated 23. The members 24 in this form of the invention are mounted at their rear ends each in a separate yoke 25 by means of a vertical pintle 26. So far as the action of the blades 100 go, however, propulsion of the boat is secured in precisely the same manner as for the construction shown in Figs. 2 and 6. In the position shown in Fig. 7, the blades are 105 approximately at their median position, the port blade moving over to starboard while the starboard blade is moving over to port, the blades, however, having not yet crossed. The blades are intended to be oscillated by 110 precisely the same mechanism heretofore described.

In some cases it is desirable that the blades shall be so formed that they may have a rocking motion as well as an oscillating motion so as to secure a still better sculling action and to this end I have illustrated in 115 Figs. 7 and 8 each blade 20^a as formed at its forward end with a forwardly projecting pivot member 27 having a ball 28 at its extremity which fits in the socket 29 formed in a vertical member 30 which has free rotation 120 upon the pintle 23. The rear end of each blade 20^a is also connected by means of a universal joint to the corresponding member 24, said member being formed with a socket 31 and the blade 20^a with a ball fitting on 125 said socket.

Sculls pivotally hinged for rotation upon

their axes may be applied at the bottom of a hydro-plane type of boat and extend for a full half length at the rear of the boat where simply great speed is desired. Such 5 sculls will be much more effective than any type of ordinary propeller as at present used with the same amount of horse-power.

For the purpose of reversing the movement of the vessel or backing it, it will be 10 necessary either to provide a set of my sculling blades at the bow of the boat in addition to the sculling blades disposed at the stern of the boat or to provide a separate propeller capable of being reversed, 15 such as that illustrated in Fig. 1. I do not, however, limit myself in this matter.

While I am not limited to any particular means for securing the sculling action of the blades, I have illustrated the connecting rod 20 from the eccentric as being attached to the blade at a point above or below its pivotal center so that as the connecting rod moves in one direction it will force, for instance, the lower portion of the blade inward and when 25 it moves in the other direction will force the lower portion of the blade outward. It will be understood that the connecting rod to one blade on one side of the boat will be attached above the longitudinal axis of the 30 blade and that on the opposite side it will be attached below the longitudinal axis of the blade.

While I have illustrated blade centralizers as applied to each one of the blades, I wish 35 it understood that this is not necessary except in vessels of relatively heavy tonnage or where great speed is desired and that it is within my invention to omit these blade centralizers. It will be obvious also that 40 while I have illustrated eccentric disks for the purpose of oscillating the blades, that other means for oscillating the blades might be used. I intend my mechanism to be applied to all types of vessels either floating 45 upon or navigating beneath the water and for the propulsion of aeroplanes, aero-hydro-planes and dirigible balloons, or for any other vessel or vehicle to which the device may be applied and that I may propel these 50 sculls either by hand for small boats or by any desired form of motor or engine.

In Figs. 10 and 11, 13 and 14, I show a boat provided with oscillating sculling blades, these sculling blades being adapted 55 to be rotated around a central longitudinal axis. In these figures, 32 designates a boat of any ordinary character and having at the stern thereof a well 33 within which the propelling mechanism is illustrated as disposed. Rotatably mounted in the stern of the boat is a spherical member 34 having oppositely disposed ears 35 to which the upper 60 and lower propeller blades 36 and 37 are pivoted by means of a pintle 38. Passing 65 through the spherical member 34 are the

driving shafts 39 and 40. Each of these driving shafts carries a bevel gear at its rearward end which engages with a bevel gear 42 mounted upon a shaft 43, each shaft 43 carrying an eccentric 44 whose eccentric 70 ring 45 is connected to one of the propeller blades by means of the connecting rod 46. It will be obvious now that a rotation of the shafts 39 and 40 will cause a rotation of the shafts 43 and a reciprocation of the blades 75 36 and 37 in opposite directions. Thus when the blade 36 is moving toward the right, the blade 37 will be moving toward the left and the blades will cross each other at the middle 80 plane of the boat.

The spherical member 34 which carries the blades is adapted either to be continuously rotated or rotatably adjusted. In Figs. 10, 11 and 14 I show means for continuously rotating these blades around a longitudinal axis. To this end I provide the shafts 39 and 40 with the gear wheels 46' which mesh with a centrally disposed driving gear wheel 47. The shafts 39 and 40 pass through and are mounted in a rotatable 90 casing or drum 48 which incloses gears 46' and 47 is driven by means of a continuously rotated gear wheel or pinion 49.

The driving shaft upon which the gear 47 is mounted and the shaft upon which the gear 49 is mounted are intended to be driven from a prime mover or engine. When the drum 48 is held from rotation it is obvious that a rotation of the gear 47 will simply act to rotate the shafts 39 and 40, but when the drum 48 is rotated by means of the pinion 49, it is obvious that not only will the shafts 39 and 40 be rotated around their axes but that they will also rotate around a common axis coincident with the driving shaft upon which the gear 47 is mounted, thus giving a continuous rotation to the blades 36 and 37 around a common longitudinal axis as illustrated diagrammatically in Fig. 12. If desired, these blades 36 and 37 may be formed 105 of resilient material, the upper edge of the blade 36 being strengthened by means of the reinforced or thickened portion 36a, while the blade 37 is strengthened by means of the reinforced or thickened portion 37a. Under 110 these circumstances a rotation of the blades in the direction of the arrow, Fig. 12, will cause the blades to flex in the manner shown in Fig. 12 and thus the blades will have somewhat the action of the ordinary propeller as well as the sculling action heretofore 115 stated and the sculling action will be still more analogous to the action of a fish's tail.

The constant rotation of the sculling blades above referred to is particularly intended for use on submarines and is designed to gain an increase in speed, this advantage being due to the fact that as soon as the boat is running the water engaged by the blades forms a more or less solid mass from which 120 125 130

the boat is actually pushed. Hence the constant rotation of the blades causes the blades to "follow up" the current first created by the blades so that no power is wasted.

5 For the purpose of shifting the blades manually from a vertical to a horizontal position, to facilitate a submarine going up or coming down, I provide the same mechanism previously described but rotate the casing 48 10 by any suitable manually operated means, as for instance the worm 50 mounted upon the shaft 51 and having the crank handle 52. This permits an adjustment of the blades to any required extent. It will be understood 15 that the showing in Fig. 13 is merely to indicate a means for accomplishing the adjustment of the blades and that I may provide any suitable mechanism to this end.

In Fig. 17 I show another form of blade 20 adapted to be used in connection with the construction illustrated in Figs. 10 and 11 or in any arrangement where the blade centralizers 6 are omitted. In this form, the blade 53 is formed of a plurality of leaves. 25 Thus in the illustration there is a central leaf 54, two leaves 55 disposed one on each side of the central leaf and shorter than the latter and two leaves 56 disposed on the outside of the leaves 55 and shorter than these 30 leaves. Thus the base of the blade is comparatively rigid and the remainder of the blade flexes gradually.

In Figs. 15 and 16 I show another form of 35 sculling mechanism operating on the same principle as that heretofore described but somewhat different in construction. In these figures, 57 designates a casing disposed in the stern of a boat (and at the bow also if necessary), and passing through this casing is a propeller shaft 58 carrying at its 40 end the ordinary propeller 59. This ordinary propeller however may be omitted and is only used for backing up or reversing.

Pivottally mounted at their forward ends 45 within the casing 57 are a plurality of blades 60. As illustrated there are three blades and each of these blades is laterally concavo-convex, the convex side of the blade being inward. The blades move outward 50 radially and the casing 57 is so formed, as illustrated in Fig. 16, as to accommodate this outward movement of the blades.

The rear ends of the blades are outwardly moved by means of a reciprocating sleeve 55 61 mounted upon the shaft 58, this sleeve having links 62 which connect the middle of each blade with the sleeve. It will thus be obvious that a reciprocation of the sleeve 61 will cause an oscillation of the blades 60. As the blades move outward, water 60 will be compressed in the space between the blades and the casing and will be drawn in to the space between the blades themselves. As the blades move reversely or toward the shaft 58, water will be drawn into

the space between the blades and the casing and expelled from the space between the blades. Thus a continuous propulsion will be secured. It is obvious that any suitable means for reciprocating the sleeve 61 may 70 be used and I have shown therefore no motor operated mechanism to this end.

In Fig. 18 I show a rudder, cruciform in section and particularly adapted to be used in connection with submarines having my mechanism applied thereto. In this figure, 75 63 designates the body of the submarine, 64 a forward rudder and 65 a rear rudder.

The triple scull arrangement illustrated in Figs. 15 and 16 may either operate in 80 unison or they may be operated irregularly like the pistons in the cylinders of a motor. I do not wish to limit myself to any specific means for operating these triple 85 sculls.

Having described my invention, what I claim is:

1. As a means of propelling vessels and the like, a plurality of blades each hingedly mounted at its inner end, centralizers hinged 90 to the outer ends of the blades, and means for independently oscillating said blades and centralizers into or out of alinement with each other in a direction transverse to the length of the vessel. 95

2. The combination with a vessel, of sculling blades, each pivotally mounted at its inner end, said blades being set in staggered relation to each other, means for oscillating said blades, and blade centralizing members 100 each pivotally connected to the free end of one of the blades, the other end of each blade centralizer being mounted for reciprocation.

3. In a vessel or the like, a sculling case 105 open at one end, a plurality of opposed sculling blades disposed within said case and each hingedly mounted at its forward end for transverse oscillation, blade centralizers, one hinged to each blade, and means for supporting the opposite end of each blade centralizer for reciprocation. 110

4. In a vessel or the like, sculling blades disposed in parallel planes, a single pivot common to all the blades, vertically disposed shafts arranged at opposite sides of said 115 pivot, eccentrics on said shafts, rods connecting said eccentrics with the respectively adjacent blades, and means for rotating said shafts.

5. In a vessel or the like, a sculling case 120 open at one end and closed at the other, the side walls of the sculling case diverging from the open end thereof for a distance and then converging to the inner end of the case, sculling blades disposed in said sculling case, each blade being hingedly mounted at its forward end for transverse oscillation in opposite directions, and blade centralizers, one for each blade, hingedly connected to said blade and supported at its outer end 125 130

adjacent the open end of the sculling case for longitudinal reciprocation.

6. In a vessel, a sculling case, oppositely disposed sculling blades within said case, the inner ends of said blades being hinged 5 mounted for transverse oscillation, the blades being vertically spaced from each other, and a propeller shaft passing through said sculling case and between said blades 10 and having a propeller at its outer end.

7. In a vessel, a sculling case having an open rear end, sculling blades hinged at their forward ends adjacent the forward end 15 of the case, brackets mounted at the rear open end of the case and provided with lon-

gitudinal slots, centralizers hinged at their front ends to the rear ends of the sculling blades, pins carried by the rear ends of the centralizers engaging the said longitudinal slots, and means acting upon the sculling 20 blades to oscillate the same and the centralizers respectively connected therewith in opposite directions.

In testimony whereof I affix my signature in presence of two witnesses.
